UNITED STATES PATENT OFFICE.

JAMES MACFADDEN GASTON, OF ATLANTA, GEORGIA.

MOTOR.

SPECIFICATION forming part of Letters Patent No. 319,970, dated June 16, 1885.

Application filed August 13, 1884. (No model.)

To all whom it may concern:

Be it known that I, JAMES MACFADDEN GASTON, a citizen of the United States, residing at Atlanta, Georgia, have invented a new and useful Improvement in Motors by the 5 Power of Nitro-Glycerine, of which the following is a full, clear, and exact description, accompanied with drawings of the same.

I will describe the invention as applied to a 10 flying-machine, though I do not limit its use thereto.

The force employed is the result of the alternate explosion of small cartridges of gelatinous nitro-glycerine in each end of the cylinder, so 15 as to drive the piston back and forth at regular intervals. A limited open space between the end wall of the cylinder and the plug of the piston provides for the partial compression of the atmosphere in this space so as to form an 20 air-cushion, which obviates any shock from the play of the piston within its prescribed limits. There are two orifices in the lateral wall of the cylinder, which are closed and opened alternately by a slide moving with the piston-rod, 25 so as to retain the force of the explosion within the chamber when it occurs, and to admit of the escape of air or gases on the other side as the piston advances.

The discharge of the cartridge at either extremity of the cylinder is effected upon the 30 same principle as that of the needle-gun, the impulse to the exploder being communicated by the contact of the slide in consequential movements with the piston-rod.

The charging apparatus consists of a disk 35 corresponding in its diameter to three-fourths ($\frac{3}{4}$) that of the end of the cylinder, placed so that its margin shall overlap that of the cylinder, and revolving upon an axle attached to 40 the side of the cylinder. Within the rim of this circular disk there are a series of openings to receive the cartridges on the side next the cylinder and having only a sufficient aperture behind for the exploding-needle. A single opening in the margin of the end of the cylinder corresponding to that in the disk externally increases internally into the cavity or air-chamber, so that its walls constitute a hollow truncated cone. The cartridges, urged 45 by the force of a spring, pass from the tube of

the loader into the opening in the disk, and as each one arrives by a stage in the revolution of the disk opposite the orifice in the end of the cylinder, the stroke of a hammer is so timed and applied that the percussion causes 55 its explosion.

The automatic loader has a series of long tubes within a cylindrical receiver, which are partially filled with cartridges. Each tube has a spring in the form of a helix compressed 60 into the remote extremity, which impels the cartridges forward, so that one is thrust into the opening in the circular disk at each step made by it in its round. When one tube is emptied, the release of the helix touches a 65 spring that brings another tube into its proper position, and so the change is made until all are discharged. In the meantime the empty tubes are replaced by others that are filled, and the work goes on without intermission, 70 from hour to hour or from day to day.

The accompanying drawings form a part of this specification, and represent what I consider the best means of carrying out the invention.

Figure 1 is a horizontal central section. Fig. 2 is an end elevation of the engine. Fig. 3 is a side elevation of the same. The remaining figures are on a larger scale. Fig. 4 is a section of a portion. Fig. 5 is a sectional 80 view of one of the loading-tubes. Fig. 6 shows the exploding means cocked. Fig. 7 shows the same in the act of exploding a cartridge.

Similar letters of reference indicate like parts in all the figures.

It is important for some uses that an engine be very strong, light, and efficient, and that the fuel and apparatus for supplying the pressure be of the smallest possible weight and bulk. The cylinder A lies horizontal. A 90 piston-rod, B, extends out at each end of the cylinder, and is equipped with two connecting-rods, B' B', operating two cranks. (Not represented.) This form is not absolutely essential, but is preferable. It gives the power 95 directly to each of two upright shafts.

The explosive cartridges are brought into position one by one and exploded in small holes a, properly arranged in each end of the cylinder. The gases at high tension devel- 100

oped by the explosions drive the piston S. Liberal ports, a' a , are opened to allow the escape of the gases for the return-stroke; but those exhaust-ports are closed in time to attain a considerable cushioning of the gas at the end of the stroke. This is important in regard to the effective power produced, and also in insuring, by means shown below, the tightness of the aperture where the cartridge is introduced.

Two long revolving frames, C, are mounted with their axes parallel to that of the main cylinder, each adapted to receive a number of long thin tubes, c, which are successively filled by the attendant with cartridges m, each composed in part or in whole of gelatinous nitro-glycerine adapted to be fired by a strong concussion. Extreme care should be taken in the manufacture and testing of the cartridges not to have them liable to explode by slight heats and concussions, as they may be subjected to such before the proper isolation and placing of each cartridge in position is effected. A spring, c', urges axially the series of cartridges in each tube c.

A wheel or perforated disk, N, is set at each end of the cylinder A, and slightlylapping upon its face, with perforations n, arranged to be presented in succession, first to one of the tubes c and receive a cartridge, and then to the firing-hole a in the main cylinder. This hole being somewhat smaller at the junction secures the capsule of the cartridge to be fired. The open extremity of each capsule has its rim turned inward, presenting a circular border to the closed end of its successor in the tube, and the outlet of each tube is closed by a thin circular plate moving upon a hinged pivot at the outer margin and opened by contact with the edge of the revolving disk, so that only the one tube is open when in opposition with the aperture in the disk. When all the cartridges in a tube are discharged, the cylindrical frame is moved one notch further round by an automatic ratchet, or by other suitable means, (not represented,) and presents another tube with a fresh supply of cartridges.

After the wheel or disk N has received a cartridge and turned so as to move it out of contact with its mates, it carries it by one or more intermittent movements into a position directly opposite the firing-hole a of the cylinder. There the disk is strongly supported by an abutment, A', on the side opposite the cylinder, so as to resist the violence of the discharge. The pressure of the air or gases within the cylinder being cushioned by the approach of the piston S to this end of the cylinder, thus accumulating a considerable pressure above that of the external atmosphere, holds the cartridge outward against the abutment, so as to tightly close a small hole, e, therein. In this condition of the several parts a firing-pin, w, mounted in the abutment A', is driven inward and strikes a sharp blow on the cartridge, sufficient to certainly explode it. The gases of the explosion hav-

ing no escape flow into that end of the cylinder and greatly increase the pressure above that to which it was already raised by the cushioning, and the piston is driven with force to the opposite end of the cylinder.

The two exhaust-ports a' a are arranged, as shown, near the mid-length of the cylinder, controlled by the extended slide-valve 75 D D, which is worked by rods y', attached to the cross-heads. They connect to these rods with sufficient lost motion, so that both are opened in advance of the piston in either direction, but are closed behind it.

The firing-pins w are each subject to a slight coiled spring, w', which holds it gently back but ready to be driven inward and induce an explosion when struck by the hammer r. Each hammer is hung on a shaft, r', carrying a V-shaped cam, r², and two divergent arms, r³, attached. The rods y' carry dogs y², which engage with the arms r³, and as the piston travels in each direction cock the hammer at one end and tip the hammer at the other end alternately.

The positions of the parts are so adjusted that the explosion at either end of the cylinder A does not occur while the piston is at the extreme end of its stroke, but, on the contrary, after it has so far moved around as to bring the crank into an effective position and allow a considerable space into which the explosion may diffuse itself and thus moderate the force.

The cartridges are preferably made with metallic shells, which insure a sufficient strength to enable them to maintain their forms under all ordinary conditions. They may have the form of the percussion-caps used for small-arms or for cannons.

x are spikes or pins carried on the cross-heads and arranged to strike through the holes n in the disks N at each stroke to insure the removal of any shell or other débris which may remain after the explosion of the cartridge.

Modifications may be made in the forms and proportions within wide limits without departing from the principle or sacrificing the advantages of the invention. Parts of the invention may be used without the whole.

I propose as one modification to use flat wafers inclosed in paper properly made adhesive.

Additions may be made. I can, if desired, provide means for automatically shifting the position of the revolving frame C when the cartridges in a tube are exhausted.

I claim as my invention—

1. In an engine operated by explosives, the combination of a revolving magazine having exchangeable cartridge-holding tubes, a cylinder having end ports to receive the products of explosion, a revolving carrier adapted to receive one cartridge at a time and convey it to said cylinder ports, and means for automatically feeding the cartridges forward and for exploding them, as set forth.

2. In an engine operated by explosives, sub-

stantially as described, a cylinder, A, having end ports to receive the products of explosion and exhaust-ports a' , located near the center, combined with a slide, D, and connections with the piston, whereby the said ports a' are closed and disclosed automatically to exhaust the gases and to cushion the piston-stroke, as set forth.

3. In an engine, substantially as described, the combination, with the magazines, the carriers, and cylinder A, having ports a' and a' , of the piston, the slide D, the pins x , the firing mechanism, and connections, as and for the purposes set forth.

15 4. In an engine for operating by explosions, the carrier wheel or disk N, having cavities n , in combination with the cylinder A, having a

hole, a , and with a suitable abutment, A', and firing means r , adapted to serve with percussion-cartridges, as herein specified.

5. In an engine for operating by explosions, the series of tubes c and springs c' , in combination with the intermittently-rotated frame C, disks or carriers N, cylinder A, and piston S, as herein specified.

In testimony whereof I have hereunto set my hand at Atlanta, Georgia, this 25th day of January, 1884, in the presence of two subscribing witnesses.

JAMES MACFADDEN GASTON.
